HINGE

James T. Atwood, Rockford, Ill.

Application May 13, 1933, Serial No. 670,951

11 Claims. (Cl. 296—44)

This invention relates to hinges for the doors of motor vehicles, and is particularly concerned with a novel hinge and method of mounting the same with a view to minimizing the extent of projection of the hinge from the body and making the hinge less conspicuous and more pleasing in appearance.

In my applications, Serial Nos. 665,404 and 668,517, I disclosed a hinge and mounting affording substantially complete concealment as well as a substantially flush exterior on the body at the hinges. The principal object of the present invention is to provide a similar hinge and mounting with what might be termed semi-concealment, since the hinges preferably project from the body to a small degree. Despite the projection, however, I have aimed with my present invention to keep concealed the uncovered back of the knuckle portions which, with the old practice, was left exposed and presented an unsightly appearance.

Other objects and advantages of my invention will be brought out in the course of the following detailed description, in which reference is made to the accompanying drawings, wherein—

Figure 1 is a side view of a portion of an automobile body showing the external appearance secured at the hinges with the construction of my invention;

Fig. 2 is a horizontal section on the line 2—2 of Figure 1, showing the semi-concealed hinge and the novel method of mounting the same;

Figs. 3, 4, and 5 are sections similar to Fig. 2 showing modified or alternative constructions;

Fig. 6 is a vertical section on the line 6—6 of Fig. 4, and

Fig. 7 is another horizontal section showing a further modified or alternative construction.

Similar reference numerals are applied to corresponding parts throughout the views.

Referring first to Figures 1 and 2, 10 indicates a portion of an automobile body on which a door 11 is hinged. The hinges provided in accordance with my invention are more or less in concealment at the points 12 and 13 where the jogs occur in the joint line 14 between the door and body. One of the hinges clearly appears in Fig. 2 and it will be seen from a study of this view that there is very slight projection of the hinge from the outside of the body in this particular form. This hinge is of the ordinary butt type and comprises a straight inner member 15 and straight outer member 16 having knuckles pivotally connected by a pintle 17. The pillar 18 of the body 10 has a pressed-in portion 19 deep enough to

accommodate the hinge entirely behind the plane of the outside of the door and body so that the door panel, a portion of which is shown at 20, and the hinge cover 21 come almost flush with the body panel 22, in keeping with the spirit of this design, the panel 20 at least being flush with the body panel 22, and the cover 21 on the hinge projecting slightly as indicated. The inner member 15 is fastened to the pillar 18 in the bottom of the pressed-in portion 19, as by screws 23 which thread into a reinforcing member 24, welded or otherwise suitably secured on the inside of the pillar. The inner member is relatively short and the outer member elongated, the latter extending beyond the end of the inner member behind the marginal flange 25 of the door and through an opening 26 in the door frame to permit fastening the same onto a reinforcing member 27 of angular cross-section, welded or otherwise suitably secured on the inside of the door frame. Cap 75 screws 28 are entered freely through holes in the reinforcement from the inside of the door frame and threaded directly in holes in the outer hinge member. This fastening is, of course, attended to before the interior finish is applied to the door. Lock washers are preferably provided for all of the fastening screws although they are shown only under the heads of the screws 28. The flange 25, previously referred to, is formed by folding the edge of the door panel 20 over the outwardly bent edge of the door frame and suitably welding the same thereto. This flange is accommodated in the rabbet 29 in the door pillar and offers protection from the weather for the joint between the door and the body, the usual seals being provided as part of the interior finish to close the joint from the inside. The cover 21 is simply a stamped sheet metal member formed with a slight crown, as indicated, for neatness in appearance and having opposed top and bottom flanges welded, as indicated at 30, to the adjacent edges of the outer hinge member. This cover will, of course, be finished to match the door and body panels or else to give some desired contrast. There is an opening 31 in the body panel at the recessed portion 19 of the door pillar large enough to allow for operating clearance around the hinge.

The foregoing description should suffice to show that the present invention provides an extremely practical as well as economical automobile door hinge and mounting therefor. The hinge being semi-concealed requires no finishing whatever and can be finished at very low cost as compared with exposed hinges. Furthermore, the general 110

appearance of the car is greatly improved by virtue of this mounting of the hinges and the external appearance going with it. Then, too, considering the fact that the greatest strains are imposed on the hinges in the running of the car, the present invention offers greater rigidity for the door because of the fact that the hinges are disposed substantially in the plane of the door as distinguished from the old practice of having them in a plane at right angles to the door. Obviously, there are no complications involved in the assembling nor in the construction of the pressed steel door and body and there is no weakening of any part by reason of what little special forming is necessitated. The door can be adjusted to a central position in the door opening before the screws 28 are tightened and in that way any slight irregularity in the mounting of the hinges on the body is compensated for, the adjustability being provided by virtue of the holes in the reenforcing members 27 being larger than the shanks of the screws, as shown.

Before proceeding any further, it should be understood that the construction just described and those later to be described may be reversed with relation to the door and body without departing from the spirit of my invention. That is to say, while 10 designates the body and 11 the door, the part designated 10 might be considered the door and the part 11 the body, it being immaterial which part of the assembly shown is swung relative to the other. The claims must be construed accordingly.

The construction disclosed in Fig. 3 is quite similar to that of Fig. 2 but instead of an ordinary butt type hinge embodies a covered joint hinge so that there is no need for a separate cover 21. In other words, the inner hinge member 15' has a knuckle portion received within the cover 21' formed on the end of the outer hinge member 16', a pintle 17' being entered through the top and bottom flanges 32 of the outer hinge member and through the knuckle of the inner hinge member to pivotally connect said members. The cover portion 21' and the adjacent portion of the outer hinge member left exposed will, of course, be finished to match the door and body panels or else to give some desired contrast. In this construction, it will also be observed that the hinge projects farther from the body, the pintle 17 being disposed with its axis approximately in the plane of the outside of the door and body portions. This projection is, however, not enough to leave the uncovered back of the hinge knuckles exposed, only the cover portion being left exposed. This gives the much desired finished appearance. The outward displacement of the hinge pintle enables shortening up the hinge arms to the extent indicated from a comparison of Figs. 2 and 3, and still allow for clearance of the flanged edge 25 of the door with respect to the bulge in the body referred to in the other two applications mentioned above.

Figs. 4-6 show other constructions quite similar to that of Fig. 3, especially adapted for use on cars which do not have the flanged doors and rabbed pillars. In Figs. 4 and 6, a covered joint hinge similar to that of Fig. 3 is shown in which the inner member 15a is straight but disposed at an acute angle with respect to the plane of the door and body portions on an angled seat 33 provided on the door pillar and fastened by screws 23 to a reenforcing member 24 welded, or otherwise suitably secured, on the inside of the door pillar. The outer hinge member 16a is bent

at about the middle to provide a portion 34 in parallelism with the inner member 15a and another portion 35 in the plane of the door and body portions, fastened to a reenforcing member 27 by screws 29 after the manner of Figs. 2 and 3. The portion 34 projects from the body and has the end thereof formed with a cover 21a enclosing the knuckle 36 of the inner hinge member. The usual pintle 17a is entered through the top and bottom flanges 32 on the outer hinge member and through the knuckle 36 of the inner hinge member to pivotally connect said members. The portion 34 of the outer hinge member will, of course, be finished to match the finish of the door and body panels 20' and 22', respectively, or else to secure some desired contrast. It is apparent from an inspection of Fig. 4 that there are no unsightly portions of the hinge left exposed so that the hinges present a neat workmanlike appearance.

The hinge of Fig. 5 corresponds to that of Fig. 4 with the exception that it is an ordinary butt type hinge composed of an inner member 15b and an outer member 16b having a separate cover 21b fitting over the exposed portion of the outer hinge member and having top and bottom flanges 37 welded, or otherwise suitably secured to the edges of the outer hinge member, as indicated at 38. The cover may, of course, be formed to any desired shape. It is shown as having a slight crown on the face thereof. The cover will be finished to match the door and body panels 20' and 22', respectively, or to present some desired contrast. With this construction, it should also be apparent that no unsightly portion of the hinge is left exposed although the hinge projects from the body to the extent shown.

The hinge shown in Fig. 7 is similar to that of Figs. 3-5 to the extent that it is a covered joint hinge whose cover has the edge thereof next to the outside of the body so as not to leave exposed any portion of the inner hinge member, whereby to give a neat workmanlike appearance. This hinge, however, has much more projecting from the outside of the body by virtue of its special construction. The inner hinge member 15c instead of being fastened to the front wall of the door pillar 18' is disposed on the side of the pillar and fastened by screws 23' to a reenforcing member 24' welded, or otherwise suitably secured, on the inside of the pillar. The outer end of the member 15c is bent at right angles, as indicated at 39, and provided with knuckles to receive the pintle 17 for pivotally connecting the inner hinge member with the companion knuckles 130 on the outer hinge member 16c. The latter is fastened to the edge of the door by screws 28' entered in a reenforcing member 27' welded, or otherwise suitably secured, on the inside of the door frame and the outer end thereof is bent at 135 right angles, as indicated at 40, so as to enclose the bent portion 39 of the inner hinge member. The portion 40 terminates in a curved cover 21c enclosing the knuckles on the inner and outer hinge members so that nothing of an unsightly 140 nature is left exposed, looking at the sides of the parts. A top plate 41, which is straight on the edge lying next to the door and body panels 20'' and 22'', respectively, has the rest of its edges curved to correspond to the shape of the outer hinge member, the plate being welded, or otherwise suitably secured, to the top edge of the outer hinge member, as indicated at 42. A hole is, of course, provided in the plate 41 to receive the pintle 17. While I have described an outer hinge

- member of this particular construction it should, of course, be understood that I am not confined thereto inasmuch as the covering of the outer hinge member, instead of being in part integral 5 with the member, might be formed entirely integral with said member or else a separate sheet metal cover might be provided to enclose the outer hinge member from the top and sides or from the top, bottom, and sides. The structures 10 of Figs. 3 and 4 are examples of hinges having cover means entirely integral with the outer hinge member. The structures of Figs. 2 and 5 are examples of hinges having separate covers. It is thought, therefore, that the different variations 15 possible with Fig. 7 are readily apparent. In passing, it will be noticed that the door is shown as provided with a flange 25 fitting in a rabbet 29 in the door pillar, and that a depression 43 is shown formed in the body panel 22" to afford operating clearance for the outer hinge member. 20 It is believed the foregoing description conveys a good understanding of the objects and advantages of my invention, and the appended claims have been drawn with a view to covering all 25 legitimate modifications and adaptations.
- I claim:
1. In an automobile construction, a body portion, a door portion, and a hinge for hingedly supporting the door portion on the body portion, 30 said hinge comprising pivotally connected inner and outer hinge members mounted on the door and body portions, the outer hinge member having a projecting cover enclosing the end of the inner hinge member and terminating substantially in the plane of the door and body portions so as not to leave any portion of the inner hinge member exposed. 35
  2. In an automobile construction, the combination of a body portion, a door portion arranged 40 to swing on a substantially vertical axis relative to the body portion, the meeting edges of the door and body portions defining a substantially straight joint line in a transverse vertical plane, a hinge for hingedly supporting the door on the 45 body, the hinge comprising a pintle laterally spaced with respect to the joint line and disposed substantially in the plane of the outside of the door and body portions, and inner and outer hinge members carried on the door and body portions 50 and pivotally connected together by said pintle, the outer hinge member projecting outwardly from the plane of the body and having a cover thereon to enclose the end of the inner hinge member, the cover reaching to a point substantially in the plane of the outside of the 55 door and body portions whereby to completely conceal the inner hinge member. 60
  3. In combination, a car body comprising a door pillar, a door swingable on the pillar as a support, and a covered joint hinge comprising inner and outer members mounted on portions 65 of the door pillar and door with their pivotally connected portions projecting outwardly from the plane of the body and disposed in a plane substantially parallel to the plane of the outside of the door and body so that the cover portion of the outer hinge member terminates close enough to the plane of the outside of the body 70 to conceal the inner hinge member, leaving only the outer hinge member exposed to view when the door is closed. 75
  4. In an automobile construction, the combination of a body portion, a door portion arranged to swing on a substantially vertical axis relative to the body portion, the meeting edges
- of the door and body portions defining a substantially straight joint line in a transverse vertical plane, and a hinge for hingedly supporting the door on the body, the same comprising inner and outer hinge members mounted on the door and body portions and pivotally connected together by a pintle, the outer hinge member being bent so as to project from the plane of the outside of the body and dispose the hinge pintle on the outer end thereof in laterally spaced relation to the joint line and substantially in the plane of the outside of the door and body portions. 80
5. In an automobile construction, the combination of a body portion, a door portion arranged to swing on a substantially vertical axis relative to the body portion, the meeting edges of the door and body portions defining a substantially straight joint line in a transverse vertical plane, and a hinge for hingedly supporting the door on the body, the same comprising inner and outer hinge members mounted on the door and body portions and pivotally connected together by a pintle, the outer hinge member being bent so as to project from the plane of the outside of the body and dispose the hinge pintle on the outer end thereof in laterally spaced relation to the joint line and substantially in the plane of the outside of the door and body portions. 85
6. In combination, a car body comprising a door pillar, a door swingable on the pillar as a support, the meeting edges of the door and body portions defining a substantially straight joint line in a transverse vertical plane, panels on the door and body portions substantially flush with one another, the body portion having hinge openings provided in the panel thereof adjacent the door and forming jogs in the joint line, and a hinge disposed in each of said openings comprising inner and outer members fastened to the pillar and door, respectively, and pivotally connected together by a pintle, the latter being disposed substantially in the plane of the outside of the door and body portions so that the outer hinge member projects correspondingly to a small extent from the plane of the outside of the body. 90
7. In combination, a car body comprising a door pillar, a door swingable on the pillar as a support, the meeting edges of the door and body portions defining a substantially straight joint line in a transverse vertical plane, panels on the door and body portions substantially flush with one another, the body portion having hinge openings provided in the panel thereof adjacent the door and forming jogs in the joint line, and a hinge disposed in each of said openings comprising inner and outer members fastened to the pillar and door, respectively, and pivotally connected together by a pintle, the latter being disposed substantially in the plane of the outside of the door and body portions so that the outer hinge member projects correspondingly to a small extent from the plane of the outside of the body, the outer hinge member having a cover portion concealing the joint between the inner and outer hinge members. 100
8. In combination, a car body comprising a door pillar, a door swingable on the pillar as a support, the meeting edges of the door and body portions defining a substantially straight joint line in a transverse vertical plane, panels on the door and body portions substantially flush with one another, the body portion having hinge openings provided in the panel thereof adjacent the door and forming jogs in the joint line, and a hinge disposed in each of said openings comprising inner and outer members fastened to the pillar and door, respectively, and pivotally connected together by a pintle, the latter being disposed substantially in the plane of the outside of the door and body portions so that the outer hinge member projects correspondingly to a small extent from the plane of the outside of the body, the outer hinge member having a cover portion concealing the joint between the inner and outer hinge members. 105

line in a transverse vertical plane, panels on the door and body portions substantially flush with one another, the body portion having hinge openings provided in the panel thereof adjacent the door and forming jogs in the joint line, and a hinge disposed in each of said openings comprising inner and outer members fastened to the pillar and door, respectively, and pivotally connected together by a pintle, the latter being disposed in laterally spaced relation to the joint line so that the inner and outer hinge members are disposed substantially in the plane of the door and body portions, and a cover on the outer hinge member extending from the pintle laterally and terminating at the joint line.

9. In combination, a car body comprising a door pillar, a door swingable on the pillar as a support, the meeting edges of the door and body portions defining a substantially straight joint line in a transverse vertical plane, panels on the door and body portions substantially flush with one another, the body portion having hinge openings provided in the panel thereof adjacent the door and forming jogs in the joint line, and a hinge disposed in each of said openings comprising inner and outer members fastened to the pillar and door, respectively, and pivotally connected together by a pintle, the latter being disposed substantially in the plane of the outside of the door and body portions so that the outer hinge member projects correspondingly to a small extent from the plane of the outside of the body, and a cover on the outer hinge member extending laterally from the pintle and terminating at the joint line.

10. In combination, a car body comprising a

door pillar, a door swingable on the pillar as a support, the meeting edges of the door and body portions defining a substantially straight joint line in a transverse vertical plane, a hinge comprising inner and outer members fastened to the adjacent edges of the door and pillar and projecting outwardly from the plane of the door and body, the outer end of the inner member being bent laterally and the outer end of the outer hinge member being correspondingly bent whereby to dispose the pivotally connected knuckle portions thereof in laterally spaced relation to the joint line and close to the plane of the outside of the door and body, and cover means for said outer end portions terminating substantially flush with the outside of the door and body.

11. In combination, a car body comprising a door pillar, a door swingable on the pillar as a support, the meeting edges of the door and body portions defining a substantially straight joint line in a transverse vertical plane, a hinge comprising inner and outer members fastened to the adjacent edges of the door and pillar and projecting outwardly from the plane of the door and body, the outer end of the inner member being bent laterally and the outer end of the outer hinge member being correspondingly bent whereby to dispose the pivotally connected knuckle portions thereof in laterally spaced relation to the joint line and close to the plane of the outside of the door and body, and cover means for said outer end portions carried on the outer hinge member and terminating substantially flush with the outside of the door and body.
